DIVING BOARD

Carl R. Meyer, 2512 E. Vine St.,
West Covina, Calif. 91722

Filed Oct. 2, 1967, Ser. No. 8,816

Term of patent 14 years

(Cl. D13—1)

FIGURE 1 is a perspective view of a diving board showing my new design as seen from the right rear;

FIGURE 2 is a full side elevational view of the diving board of FIGURE 1;

FIGURE 3 is a top plan view of the diving board as shown in FIGURE 1;

FIGURE 4 is a bottom plan view of the diving board as seen in FIGURE 1;

FIGURE 5 is a rear end elevational view of the diving board as shown in FIGURE 1;

FIGURE 6 is a front end elevational view of the diving board as shown in FIGURE 1;

FIGURE 7 is a cross-sectional view of the diving board as shown in FIGURE 1 taken along a line 7—7 of FIGURE 3; and

FIGURE 8 is a cross-sectional view taken along a line 8—8 of FIGURE 7.

The dominant features of my design are shown in full lines. The supports shown in FIGURE 1 in dotted lines have been omitted from the other views for convenience of illustration only.

I claim:

The ornamental design for a diving board, as shown and described.
